CLAIM

The ornamental design for a illuminated fishing pole, as shown and described.

DESCRIPTION

FIG. 1 is a front elevational view of the illuminated fishing pole showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an isometric view thereof;

FIG. 8 is an enlarged perspective view of the end of the rod, the remainder of the rod and handle having been cut away for the convenience of illustration; and,

FIG. 9 is an elevational view thereof.

FIG. 1

FIG. 2

FIG. 3

FIG. 4

FIG. 5

FIG. 6
